LIMITED, OF LONDON, ENGLAND.

CYLINDER FOR INTERNAL-COMBUSTION ENGINES.

1,309,103.

Specification of Letters Patent.

Patented July 8, 1919.

Application filed September 24, 1917. Serial No. 192,960.

To all whom it may concern:

Be it known that I, ARTHUR JOHN Rowledge, a subject of the King of England, residing at London, in England, have invented 5
certain new and useful Improvements in Cylinders for Internal-Combustion Engines, of which the following is a specification.

This invention relates to cylinders for internal combustion engines more particularly 10 those in which the inlet and exhaust passages and the water jacket are formed of aluminium or aluminium alloy while the cylinder itself is formed of steel and has for its object to simplify the construction and obviate certain difficulties due to the different 15 co-efficients of expansion of the metals employed.

In constructing cylinders of the type indicated in order to insure soundness in the 20 aluminium or aluminium alloy castings it is desirable to make these castings as simple as possible. Further it is advisable to leave the steel cylinder as free as possible for purposes of expansion. It has previously been proposed to insert a steel cylinder into a water jacket formed of aluminium or aluminium alloy cast integral with a head portion in which are the inlet and exhaust passages 25 the cylinder head being connected to the head portion of the casting by tubular flanged members forming the valve seats which were passed through openings in the cylinder head and screwed into the casting. In that case, however, the head of the cylinder was inclosed in the casting and consequently was not free to expand while the casting of the water jacket integral with the head portion militated against simplicity and necessitated the jacket being formed of 30 substantial thickness. The improved construction avoids these disadvantages.

According to this invention a casting of aluminium or aluminium alloy is provided in which are the inlet and exhaust passages 45 and the guides for the valve spindles and this casting is provided with a smooth face which is fitted on to the smooth flat head of a steel cylinder the casting being so formed that it rests on the head of the cylinder and does not extend along it or around the head. The casting is connected to the cylinder either in a known manner by means of flanged tubular members which form the valve seats and are passed through openings 50 in the cylinder head and screwed into the

casting, or alternatively, the casting may be bolted to the head of the cylinder. In the latter case the valve seats would be formed in the head of the steel cylinder and the bolts which would be passed through the cylinder 60 head would conveniently be disposed between the ports and possibly one of them in the center so as to keep the connection between the casting and the cylinder localized as far as possible and as near the center of 65 the cylinder as is practicable. A sheet metal casing of aluminium or aluminium alloy formed in one or two parts and constituting the water jacket is connected by welding to the casting on the cylinder head and to a 70 separate ring which surrounds the cylinder body with which it is arranged to form a tight joint. The steel cylinder is thus only directly connected to the casting mounted on its head by the valve seat members or by 75 the bolts as above mentioned and the periphery of the cylinder head and its body are left free to expand independently of the casting and the water jacket. The casting may be simple and of such a nature that 80 soundness may be insured while a minimum of metal may be employed in the formation of the water jacket.

In putting the invention into practice, for example in the construction of a block of 85 cylinders, the cylinders are mounted in a jig and the heads of all of them are smoothed off by grinding or otherwise. A spectacle frame is formed in some convenient manner, this frame comprising the several rings to 90 which the outer end portion of the water jacket casing is connected, these rings being all formed integral. This frame is slipped over the cylinders. The face of the casting for the heads of all the cylinders is similarly 95 smoothed off and the casting applied to the heads of the cylinders and fixed in place by screwing in the tubular valve members or by bolting the parts together. The sheet metal casing constituting the water jacket is 100 conveniently formed in two parts each adapted to inclose all the cylinders along one side. These two casing parts are applied to the cylinder and the end portions of the casing are united by welding. The casing 105 is now brought up against a flange provided for the purpose on the under side of the head casting and welded to this flange. At a suitable point in its length each cylinder has been formed with an external annu- 110

lar groove or recess as for instance by providing twin radial flanges and into this recess is inserted a ring of dermatin or other suitable material. The spectacle frame is now brought over the recess containing the dermatin ring with which it forms a tight joint and the frame is connected by welding to the end part of the water jacket casing.

- 10 The detail formation of the casting which is mounted on the head of the cylinder may vary in accordance with requirements. The detail construction of the steel cylinder may also vary as found desirable. The head of this cylinder is conveniently thickened in the usual manner and toward its outer end there is formed on the exterior of the cylinder a flange or foot for the purpose of attaching it to the crank casing.
- 15 20 The accompanying drawings illustrate by way of example one construction of cylinder in accordance with this invention. In these drawings,

Figure 1 is a longitudinal sectional elevation through the cylinder and head casting.

Figs. 2 and 3 show modifications in the method of connecting the cylinder water jacket to the head casting.

Fig. 4 is a longitudinal sectional elevation through the end of the cylinder and head casting illustrating a modification in the method of connecting the head of the cylinder to the casting.

Fig. 5 is a section on the line 5—5 of Fig. 4 looking in the direction of the arrows.

Like letters indicate like parts throughout the drawings.

The cylinder A is formed of steel with an integral head A' in which are formed openings adapted either to constitute valve seats or to receive separately formed valve seats as in the construction illustrated. The outer face of the cylinder head A' is formed flat and smooth and this head together with some portion of the body of the cylinder which extends from the head and incloses the combustion space is conveniently thickened in the usual way. Toward the open end of the cylinder is preferably formed on its exterior a flange or foot A² which serves to attach the cylinder to the crank casing.

The head casting B is formed of aluminium or aluminium alloy and is provided with inlet and exhaust passages B' and guides C for the valve spindles. This head casting has a smooth face B² adapted to fit on to the smooth cylinder head A' the casting being so formed that it rests on the head of the cylinder and does not extend along its body or around the head. The casting B is connected to the cylinder by means of the flanged tubular members D each of which forms a valve seat and is passed through an opening in the cylinder head A' and

screwed into the casting B. Alternatively the valve seats may be formed in the cylinder head A' and bolts are then passed through the head of the cylinder into the casting these bolts being disposed between the ports one of them being conveniently situated in the center of the cylinder. The bolts are so positioned as to maintain the connection between the cylinder and the casting as near as possible to the center of the cylinder.

A sheet metal casing E is formed of aluminium or aluminium alloy either in one or two parts and constitutes the water jacket which surrounds the cylinder body. This casing may be connected to the outer portions B³ and B⁴ of the head casting B by welding as shown in Fig. 1. Alternatively as shown in Figs. 2 and 3 the end of the casing E may be connected to the parts B³ and B⁴ by flanging outwardly the end of the casing E and passing screws F through this flange into the parts B³ B⁴ which are then suitably shaped as shown.

A separate ring G is provided and constructed so as to surround the cylinder A at some point in its length where there has been formed on the cylinder two annular flanges A³. In the groove formed between these flanges A³ is placed a ring H of dermatin or similar material of such dimensions that when the ring G is in place a tight joint will be formed between it and the cylinder A. The end of the casing E is welded to the ring G.

It will thus be seen that the only direct connection between the cylinder A and the head casting B is at the head A' of the cylinder and the connection is situated as near the center of the cylinder head as possible so that the periphery of the cylinder head and the cylinder body are left entirely free to expand independently of the head casting B and the water jacket E.

When applying the invention to a construction comprising a set or block of cylinders, a single integral head casting B is provided for all the cylinders A which are separately attached thereto in the manner described. The ring G for the several cylinders is formed in one piece as a spectacle frame. The sheet metal casing E is then conveniently constructed in two parts each of which closes in one side of the block of cylinders; the end of the two parts of the casing being connected together by screws or by welding. The connections between the casing and the head casting B and the spectacle frame G may be made as indicated above.

In the modification illustrated in Figs. 4 and 5 the head A' of the cylinder A is connected to the head casting B by a series of bolts or studs J in place of the tubular valve seat members D. These studs are screwed

into the head casting B so as to project from its flat face and the ends of the studs pass through corresponding holes formed in the head A' of the cylinder nuts J' being screwed 5 on to the ends of the studs so as to draw and hold the head casting B closely against the end of the cylinder. As shown in Fig. 5 the studs J are located between the ports A² in the cylinder head A' one of these studs being 10 positioned in the center while the others are arranged as near as possible to the center. In the construction illustrated the cylinder is provided with four ports A² controlled by valves the seatings for which are formed 15 directly in the head A' of the cylinder in place of in separate members such as D as in the construction illustrated in Fig. 1.

What I claim as my invention and desire to secure by Letters Patent is:-

20 1. In a cylinder for an internal combustion engine the combination of a steel cylinder having a smooth flat head, inlet and exhaust openings in the head of this cylinder, a casting of aluminium or aluminium alloy 25 in which are formed inlet and exhaust passages and in which are arranged guides for the valve spindles this casting having a smooth face adapted to fit accurately on to the head of the cylinder with the openings 30 of the inlet and exhaust passages in the casting coincident with the openings in the cylinder head the casting being so formed that it rests on the cylinder head and does not extend along the cylinder or around the head, 35 a plurality of members passing through the cylinder head and screwed into the casting and serving as the only rigid connection between the cylinder and the casting, a plurality of valves controlling the inlet and exhaust 40 openings in the cylinder head with their spindles passing through the guides in the casting, a separate ring member surrounding the body of the cylinder, means by which a water tight joint is formed between 45 this ring member and the cylinder body at some place in the length of the latter, and a sheet metal casing formed of aluminium or aluminium alloy and constituting the cylinder water jacket one end of this casing being 50 connected to the casting on the head of the cylinder while the other end is connected to the ring member as set forth.

2. An internal combustion engine construction including in combination, a steel 55 cylinder having one end closed by a thin head formed with inlet and exhaust openings, the outer surface of said head being flat, a casting of aluminium formed with a flat surface having inlet and exhaust 60 passages opening therethrough, means securing the casting to the cylinder head with said flat surfaces only in contact and the inlet and exhaust openings in communication with the inlet and exhaust passages, a casing 65 of aluminium secured to the casting and sur-

rounding the cylinder forming a water jacket, the end of said casing opposite the casting having a water tight connection with the cylinder.

3. An internal combustion engine construction including in combination, a steel cylinder having one end closed by a thin head formed with inlet and exhaust openings, the outer surface of said head being flat, a casting of aluminium formed with a 70 flat surface having inlet and exhaust passages opening therethrough, means securing the casting to the cylinder head with said flat surfaces only in contact and the inlet and exhaust openings in communication with the inlet and exhaust passages, a casing 75 of aluminium secured to the casting and surrounding the cylinder forming a water jacket, a ring secured to the end of said casing opposite the casting and having a sliding water tight connection with the cylinder.

4. An internal combustion engine construction including in combination, a steel cylinder having one end closed by a thin head formed with inlet and exhaust openings, the outer surface of said head being flat, a casting of aluminium formed with a 80 flat surface having inlet and exhaust passages opening therethrough, means securing the casting to the cylinder head with said flat surfaces only in contact and the inlet and exhaust openings in communication with the inlet and exhaust passages, said means being disposed substantially along a 85 diameter of said head, a casing of aluminium secured to the casting and surrounding the cylinder forming a water jacket, the end of said casing opposite the casting having a water tight sliding connection with the cylinder.

5. An internal combustion engine construction including in combination, a steel cylinder having one end closed by a thin head formed with inlet and exhaust openings, the outer surface of said head being 90 flat, a casting of aluminium formed with a flat surface having inlet and exhaust passages opening therethrough, means securing the casting to the cylinder head with said flat surfaces only in contact and the inlet and exhaust openings in communication with the inlet and exhaust passages, said means being disposed substantially along a 95 diameter of said head, a casing of aluminium secured to the casting and surrounding the cylinder forming a water jacket, the end of said casing opposite the casting having a water tight sliding connection with the cylinder.

6. An internal combustion engine construction including in combination, a steel cylinder having a thin head closing one end formed with a flat exterior surface, an aluminium casting having a flat surface, means 100 extending through said head within the con- 105

5 fines of the bore of said cylinder for securing the casting to the cylinder with said flat surfaces only in contact, an aluminium casting surrounding and spaced from the cylinder secured at one end radially outside the cylinder to the casting and having a water tight sliding connection with the cylinder at its other end.

- 10 7. An internal combustion engine construction including in combination, a steel cylinder having one end closed by a thin head formed with inlet and exhaust openings, the outer surface of said head being flat, a casting of aluminium formed with a 15 flat surface having inlet and exhaust passages opening therethrough, means securing the casting to the cylinder head with said flat surfaces only in contact and the inlet

and exhaust openings in communication with the inlet and exhaust passages, said 20 means comprising solely rings extending through said openings and secured to the casting, puppet valves carried by the casting each adapted to seat on one of said rings, a casing of aluminium secured to the casting 25 and surrounding the cylinder forming a water jacket, the end of said casing opposite the casting having a water tight sliding connection with the cylinder.

25 In testimony whereof I have signed my 30 name to this specification in the presence of two subscribing witnesses.
